(No Model.)

P. VIGIL & J. N. REVUELTA.

SHOAL WATER INDICATOR.

No. 389,123.

Patented Sept. 4, 1888.

UNITED STATES PATENT OFFICE.

PEDRO VIGIL AND JUAN N. REVUELTAS, OF MEXICO, MEXICO.

SHOAL-WATER INDICATOR.

SPECIFICATION forming part of Letters Patent No. 389,123, dated September 4, 1888.

Application filed March 7, 1888. Serial No. 266,469. (No model.)

To all whom it may concern:

Be it known that we, PEDRO VIGIL and JUAN N. REVUELTAS, both of the city of Mexico, Mexico, have invented a new and Improved Electric Sounding-Line, of which the following is a specification, reference being had to the annexed drawings, forming a part thereof, in which—

Figure 1 is a vertical transverse section of the contact-maker of our improved sounding-line. Fig. 2 is a vertical transverse section of the cap of the circuit-closer. Fig. 3 is a plan view of the cap, and Fig. 4 is a horizontal section taken on line *xx* in Fig. 1.

Similar letters of reference indicate corresponding parts in all the views.

The object of our invention is to construct a simple and effective electrical device for taking soundings.

Our invention consists in the combination of a metallic vessel, a central tube of non-conducting material, having at its ends electrical conductors, a body of mercury placed in the non-conducting tube, heavy material surrounding the non-conducting tube and filling the metallic vessel, a cap closing the vessel, and an electric cable connected with the cap and with the conductors at opposite ends of the non-conducting tube, all as hereinafter more fully described.

The vessel A, forming the body of the sounding device, is preferably made of cylindrical shape, having an integral bottom, *a*. The bottom of the vessel A is provided with a wooden covering, *b*, which is chambered at its center to receive the socket *c*, in which is inserted the lower end of the tube B.

The tube B is made of insulating material, preferably of glass, and is closed at its upper and lower ends by disks *d d'* of conducting material. Within the tube B is placed a body, *e*, of mercury, which is sufficient to about half fill the tube. To the inner surface of the wall of the vessel A are secured brackets *f*, which support the plate *g*. The plate *g* is provided with a metallic collar, *h*, inclosing an elastic packing, *i*, which covers and seals the end of the tube B. Within the vessel A, surrounding the tube B, are placed lead shot *j*, which give the device sufficient weight to descend rapidly.

To the upper surface of the plate *g* is secured a hollow cylinder, *k*, the top of which is apertured to receive the end of the cable C. The cable C is looped at its lower end and fastened in the hollow cylinder *k* by a coupling-pin passing through the loop. The conductor *m* of the cable C is connected with the disk *d*, and the conductor *n* is connected with the disk *d'*.

Upon the plate *g* is placed a packing-ring, *o*, of rubber or analogous material, and to the top of the vessel A is fitted a conical head, *D*, which is rabbeted around its periphery to receive the rubber ring *o*, and is bored out conically to receive the tapering elastic packing-piece *p*, which incloses the cable C and forms a water-tight joint between the cable C and the head D. The head D is secured to the top of the vessel A by screws *q* passing through the head into the upper edges of the vessel.

The cable C communicates with a battery and sounding device—such as an electric bell—upon shipboard. The vessel A, with its contents, is suspended and maintains a vertical position below the bottom of the vessel, and when it strikes a reef or high bottom it turns upon its side and the mercury *e* establishes electrical communication between the disks *d d'*, thus causing the alarm to be given on board the vessel.

Having thus described our invention, we claim as new and desire to secure by Letters Patent—

1. The combination, with a weighted vessel, of a non-conducting tube provided with metallic contacts at its ends, a body of mercury placed in the tube and adapted to establish communication between the contacts at the ends of the tube, and a cable carrying electric conductors, substantially as described.

2. The combination, with a vessel, A, of the non-conducting tube B, provided with metallic disks *d d'*, the mercury-filling *e*, the shot *j*, the plate *g*, the head *D*, the packing-ring *o* and packing *p*, and the cable C and conductors *m n*, substantially as described.

PEDRO VIGIL.

JUAN N. REVUELTAS.
